US00D635455S

(12) **United States Design Patent**
Andre et al.

(10) **Patent No.:** US D635,455 S
(45) **Date of Patent:** ** Apr. 5, 2011

(54) **PACKAGING**

(75) Inventors: **Bartley K Andre**, Menlo Park, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Shin Nishibori**, Portola Valley, CA (US); **Matthew Dean Rohrbach**, San Francisco, CA (US); **Douglas B. Satzger**, Menlo Park, CA (US); **Calvin Q. Seid**, Palo Alto, CA (US); **Vincent Keane Seid**, legal representative, Los Gatos, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/365,020**

(22) Filed: **Jul. 1, 2010**

Related U.S. Application Data

(63) Continuation of application No. 11/849,176, filed on Aug. 31, 2007, which is a continuation-in-part of application No. 29/265,951, filed on Sep. 11, 2006, now Pat. No. Des. 558,571, and a continuation-in-part of application No. 29/265,952, filed on Sep. 11, 2006, now Pat. No. Des. 558,572, and a continuation-in-part of application No. 29/281,505, filed on Jun. 25, 2007, now Pat. No. Des. 596,485.
